UNITED STATES PATENT OFFICE.

HARRY H. PERRY, OF STOCKTON, CALIFORNIA.

DESIGN FOR A TOY AEROPLANE.

Application filed May 12, 1923. Serial No. 6,145. Term of patent 3½ years.

To all whom it may concern:

Be it known that I, HARRY H. PERRY, a citizen of the United States, residing at Stockton, in the county of San Joaquin, State of California, have invented a new, original, and ornamental Design for a Toy Aeroplane, of which the following is a specification, reference being had to the accompanying drawing, forming part thereof.

Fig. 1 is a side elevation of a toy aero-plane, showing my new design, and

Fig. 2 is a top plan view of the same.

I claim:

The ornamental design for a toy aero-plane, as shown.

HARRY H. PERRY.
